PHILIP H. BEVIER, OF NEW YORK, N. Y.

HOLLOW-TILE WALL.

1,158,362.

Specification of Letters Patent. Patented Oct. 26, 1915.

Application filed May 22, 1911. Serial No. 628,661.

To all whom it may concern:

Be it known that I, PHILIP H. BEVIER, a citizen of the United States, residing in the city of New York, borough of Brooklyn, county of Kings, and State of New York, have invented a certain new and useful Hollow-Tile Wall, of which the following is a specification.

This invention is a hollow tile wall adapted to be economically installed, and yet possessing great strength and general efficiency.

As will hereinafter appear, the wall embodies courses of hollow tiles positioned vertically, and in a manner for the tiles of one course or layer to break joints with the tiles of an adjacent course or courses, whereby the webs of said tiles serve as compression members; and, also, positioning said tiles so that the successive webs and chambers are in alinement. By alining the chambers of the hollow tiles, the courses of which break joints, continuous spaces are formed which can be filled in with concrete, with or without tension members, or further, may be employed to incase gas or water pipes, electric wiring, etc.

Other features of the invention will be readily apparent from the following detailed description read in conjunction with the drawings.

In the accompanying drawings, I have illustrated one practical embodiment of the invention, but the construction shown there-in is to be understood as illustrative, only, and not as defining the limits of the invention.

Figure 1 is a front view of a portion of a wall composed of hollow tiles assembled for the courses of tiles to break joints in accordance with this invention. Fig. 2 is a plan view of a series of tiles composing the wall of Fig. 1. Fig. 3 is a plan view showing one tile in full lines and two other tiles in dotted lines, in order to disclose the relation of the walls and webs of one tile relative to two adjacent tiles either above or below it. Fig. 4 is a perspective view on an enlarged scale, illustrating the arrangement of breaking joint tiles in accordance with this invention and showing, also, reinforced concrete in the chambers of certain of the tiles, a pipe adapted to run through the chambers of the tiles, a stucco finish on one surface of the wall,

and an interior finish on the other surface of the wall.

A designates a building block composed of burned clay in contradistinction to a molded concrete block. The block A is shown as consisting of parallel side walls a, b, parallel end walls c, d, longitudinal webs e, f, and cross webs g, h, all the parts being integral. Longitudinal chambers i are provided by the walls and the webs, as shown in Figs. 2 and 3. Four of these chambers i are provided in the block, said chambers being substantially equal in cross sectional area. The block is provided with narrow longitudinal openings j, said openings being positioned intermediate the webs g, h. The longitudinal openings j are much narrower than the longitudinal chambers i. The block is composed of fire clay, and in manufacturing the block the material is run through a suitable tile machine, the parts of which are adjusted so that the walls and webs will be produced by running the material through the machine. This requires that all the surfaces lengthwise the tile shall be substantially parallel, in order that the clay material will run through the dies of the machine. Subsequent to the production of the "green" or unbaked tile, it is placed in a kiln, for the purpose of burning the material so as to result in a complete tile. It is important that the block shall be constructed in a way to provide for the circulation of the heat in contact with the interior and exterior surfaces of the clay, and it is for this purpose that the tile is provided with longitudinal chambers i and with longitudinal openings j.

Very considerable difficulty is experienced in burning the tile uniformly. Obviously, were the longitudinal passages j omitted and the cross webs g, h solid or unbroken between adjacent chambers i, an excess of clay material would be positioned between said chambers, and it would not be possible, from a practical standpoint, to burn the tile uniformly. To overcome this objection, the tile is provided with longitudinal spaces j, for separating the cross webs g, h. The chambers i provided for the free circulation of heat within the unbaked tile, and the longitudinal spaces j enable the heat to circulate through the middle part of the tile so that the two surfaces of cross webs g, h will be baked or burned uniformly. A tile

composed of clay material and constructed as just described may be baked or burned uniformly throughout all portions thereof, so as to minimize the presence of unbaked 5 clay in the resulting tile, and to result in a tile possessing the necessary hardness, toughness and durability.

- According to my invention, a wall constructed from the hollow tile blocks is equal 10 substantially in thickness to the thickness of the individual blocks, that is to say, the thickness of the block from front to rear is about equal to the thickness of a wall resulting from an assemblage of the blocks, 15 except, of course, that the total thickness of the wall may ultimately be increased by the application either of an inside plaster coat, or of an exterior finish coat, or both, in order to impart desirable finishes to the wall. 20 The increased or larger dimensions required in hollow tile blocks to be employed in walls of this character necessitates the employment of internal webs arranged substantially as herein disclosed in order to produce a 25 block having the strength required to carry the load. It is apparent, therefore, that my invention is distinguished in structural particulars from prior blocks in two essential respects; first, by a thickened web uniting 30 the front and rear walls of the block and, second, by a cross web extending from the end walls and intersecting with said thickened web, said cross web increasing to a marked extent the strength and stability of 35 the thickened web. In the form of block herein shown, the thickened web is formed by parallel webs *g* *h* separated by the longitudinal spaces; the result being a web the thickness of which exceeds the thickness of 40 either of the walls of the block, and which exceeds, also, the thickness of the web intersecting therewith. Said thickened web is provided with longitudinal openings for the purpose herein mentioned, the width of said 45 openings being equal to the thickness of the mortar bond employed for uniting the blocks when assembled. Furthermore, in the block shown, the cross web or webs *e* *f* are continuous, the same intersecting with the thickened web and joining the walls of the block 50 at the ends thereof.

In assembling the hollow tile blocks to produce a hollow wall in accordance with my invention, the blocks are positioned on 55 end so that the walls of said blocks, the internal webs and the longitudinal chambers or passages are vertical, said blocks being assembled in rows and the blocks of adjacent rows being positioned to break joints *i. e.* 60 the vertical space separating two blocks of one row is out of alignment vertically considered with the spaces between blocks of adjacent rows. This arrangement of the blocks secures important advantages, chief 65 among which is that the walls at the ends

of each block are in vertical alignment with the thickened webs of two blocks in the rows above and below it, whereas the thickened web in said block is in vertical alignment with the end walls of two blocks in the 70 courses above and below it, and the side walls and cross webs of said block are in vertical alignment with corresponding walls and webs of the two blocks above and below it, whereby all the walls and webs of each 75 block are in register with other blocks so as to bring said walls and webs in compression and thereby increase the weight-carrying capacity of the wall. Furthermore, the chambers or cells of the superposed blocks are in vertical register, and I am thus enabled to fill said chambers, or some of them, with concrete material *C*, which material is reinforced by embedded metal rods or bars *D*, thus securing great strength for the reason 80 that the concrete material and the metal rods add substantially to the strength of the wall formed by the blocks, the latter being assembled in the novel manner described for the purpose of utilizing to the best advantage 85 the compressive strength of the clay material composing the blocks themselves.

The hollow tile blocks used in my invention for the erection of walls are positioned on end, it being essential that the blocks when 90 superposed upon each other will stand vertical. Accordingly, my wall blocks are made for the end faces thereof, or those surfaces at the open ends, to extend at a right angle to the surfaces of the side and end walls of 95 the block, and I am thus enabled to set or impose one block upon the others so that all the blocks will stand plumb and will have the required firm bearing one upon the other.

Another novel feature of the invention 100 consists in spacing or standing each tile on end, in contradistinction to laying the tile in a flat horizontal position upon its side.

The tiles are laid in courses with the tiles of one course breaking joints with the tiles 110 of an adjacent course or courses, substantially as shown in Fig. 1, whereby the desired effect is obtained in the construction of the wall.

As shown in Figs. 1 and 2, the tiles *A* are 115 positioned vertically and on end. In laying the bottom course, the tiles are placed side by side, with a mortar joint *B* between the end walls *c*, *d* of adjacent tiles. In laying the next, or second course, an end block *A'* 120 is employed at the corner or end of the course, and the other blocks composing the second course are then placed in position, in the manner illustrated more particularly in Figs. 1 and 3. Each block of the second 125 course is positioned to break joints with the blocks of the first course, and this carries into practice one of the novel features of the invention, whereby the walls and webs of the tile are brought into compression, for the 130

purpose of sustaining the weight. The end walls *c* of a superposed block are in alinement vertically with a cross web *h* of the block below it; the end wall *d* is in alinement vertically with the cross web *g* of the block below it; the cross webs *g*, *h* are in alinement vertically with the end walls *c*, *d*, respectively, of the blocks below them; the webs *e*, *f* are in alinement with similar webs of the blocks below them, and the side walls *a*, *b* are, also, in alinement vertically with corresponding walls of the blocks below them. It is apparent from this detailed explanation that all the parts of a block in the second course are in alinement with parts composing the block or blocks of the first course, and thus the solid parts of the blocks in the first and second courses are in vertical alinement, for the purpose of increased strength, rigidity and weight carrying capacity of the blocks composing the wall.

From the foregoing description taken in connection with Figs. 3 and 4 of the drawings it is apparent that, in a wall the thickness of which is equal to the thickness of the individual blocks comprising it, said blocks are assembled in a novel manner in order to secure the weight carrying capacity due to bringing the walls and webs of each block in alinement with certain of the walls and webs of two adjacent blocks in an adjoining row or rows. In my block, two cross webs *g* *h* are employed, and they are relatively spaced to produce two narrow cells *j*, the width of which is equal to the cement or mortar receiving space provided between the vertical faces of two adjacent blocks in adjoining rows. Thus, the narrow cells *j* in one block are in alinement vertically with the mortar or cement spaces between adjacent blocks in the rows above and below said block, and this enables the end walls of each block to be in alinement vertically with the two nearest cross webs *g* *h* in the two adjacent blocks of an adjoining row or rows, whereby the cross webs *g* *h* of one block will register vertically with the end walls of two adjacent blocks above or below the same, whereas the webs *e* *f* and the side and end walls of said block will register vertically with certain of the walls and the corresponding webs respectively of said two adjacent blocks. Moreover, it is evident that to secure the desired result, *i.e.* to bring the webs and walls of each block in alinement vertically with the webs and certain parts of the walls of two adjacent blocks in the adjoining row, either above or below, or both, said block is made of a length equal to the distance between the nearest cross webs in the two adjacent blocks plus the width of the mortar or cement space between said two blocks, it being evident that when said block is placed in position upon said two blocks that the narrow cell space *j* of the block will

be in vertical alinement with said mortar or cement space between the two subjacent blocks of the row or course below it.

It is evident that all the blocks of the second course should be laid in the manner described, and further, the blocks in the third, and succeeding courses, should be positioned as herein disclosed.

The assemblage of the blocks in the manner described brings the chambers *i* of each block into register with corresponding chambers in the blocks above and below it. This produces a tile wall, the chambers of which are in communication or alinement vertically, as will clearly appear from an examination of Figs. 3 and 4. The vertical chambers within the hollow tile wall are utilized for various purposes, and in Fig. 4 there is shown a construction of the wall, wherein reinforced concrete, gas or water pipes and electric conductors may be, and preferably are, incased within the chambers of said wall. When the tiles are positioned on end with their chambers in vertical alinement, some or all of the chambers may be filled with concrete *C*. Tension members *D* are embedded within the concrete, said tension members extending through the vertical chambers and the tile wall. Any suitable form of metallic tension member may be employed, such as the twisted metal rods shown at *D* in Fig. 4. Furthermore, a pipe *E* extends through the vertically alined chambers of the hollow tile wall, said pipe *E* being employed for conveying gas, water, or other medium, into or from the building; said pipe may be utilized for various other purposes. Furthermore, electrical conductors may be run through the vertical chambers of the hollow tile wall.

The wall is composed, substantially wholly, of hollow tiles placed on end and assembled in the manner described, the thickness of the wall being equal substantially to the thickness of the tiles composing it. Any suitable finish may be applied to the exterior surface and to the interior surface of the tile wall. In Fig. 4 I have shown the stucco finish *F* covering the exterior surface of the hollow tiles. The interior surface of the tile wall is covered by one or more coatings of plaster, or any other desired material, indicated at *G*. As shown, the surfaces of the tiles are provided with longitudinal grooves *A*², whereby the stucco coating *F* and the plaster coating *G* will become keyed to the tiles in order to secure a firm union or adhesion of the coating material to the tile wall. Obviously, the grooves *A*² may be omitted, and any suitable surface finish provided on the tiles composing the wall.

As described, my blocks are provided in the exposed surfaces of the side and end

walls with dovetailed grooves A². When the blocks are assembled in a wall, the grooved end walls of two adjacent blocks are in opposing or facing relation, and are 5 in register vertically with the thickened webs of the blocks above and below it, said grooved end walls of the blocks being covered with the mortar or cement bonding material, which material also fills the grooves 10 A² in said end walls, so that the bonding material is interlocked with the end walls of the blocks, the thickness of said bonding material being equal substantially to the width of the openings *j* in the thickened webs of the blocks. Owing to the comparatively rough surface of the blocks, and to impart a desirable finish to the wall, I apply an exterior coat of stucco or the like to the outer surface of the wall, and an interior 15 coat to the inner surface of said wall, the materials of said exterior and interior coatings being interlocked with the blocks for the reason that said materials enter and fill the dovetailed grooves therein.

20 The tiles are united by mortar or cement applied to the exposed vertical faces of the end walls *c*, *d*, and to the end portions of the webs and walls of the tiles, for the purpose of uniting the tiles solidly into a unitary strong wall construction.

Having thus fully described the invention, what I claim as new, and desire to secure by Letters Patent is.

1. A hollow-tile wall block the exterior 35 surfaces of which are provided with grooves and the end faces of said block being at right angles to the surfaces of the walls composing said block, said block being provided internally thereof with a thickened 40 web connecting the inner and outer walls of said block, the thickness of said web exceeding that of the walls and said block being provided, also, with cross webs extending from the end walls and intersecting 45 with said thickened web so as to form therewith individual cells extending lengthwise through the block, said thickened web being provided in the material composing it with narrow longitudinal openings, the latter being sufficiently wide to include a masonry bond adapted to unite the end 50 walls of adjacent blocks.

2. A hollow-tile wall block the ends of 55 the walls composing said block, said block being provided internally thereof with a thickened web and with a continuous cross web, said thickened web connecting the inner and outer walls of the block and the 60 cross web extending inwardly from the end walls and joined with the thickened web intermediate said inner and outer walls, the thickness of said first named web exceeding that of the separate walls of the block and

said thickened web being provided in the 65 material composing it with openings the transverse width of which is less than that of the individual cells.

3. A wall comprising hollow tile blocks bonded together in rows for the blocks of 70 one row to break joints with the blocks of adjacent rows, each hollow block being provided internally thereof with a thickened web and with a cross web positioned relatively to each other to produce cells extending lengthwise of the block, said thickened web connecting the inner and outer walls of the block and being provided in the material composing it with openings the width of which is equal substantially to the thickness of the bonding material uniting two adjacent blocks on the opposing end walls thereof, the end faces of said hollow block being at right angles to the surfaces of the walls composing said block and said blocks 80 being vertically positioned for the walls and webs of each block to aline vertically with some of the walls and webs of two blocks below it.

4. A wall comprising hollow tile blocks 90 each provided on the outer surfaces of the walls composing it with grooves and provided internally thereof with a thickened web and with a cross web which latter web connects with the end walls and with the 95 thickened web intermediate the inner and outer walls, the thickness of said thickened web exceeding that of the separate walls of the block and said thickened web being provided in the material composing it with 100 longitudinal openings the width of which is equal substantially to the thickness of the bonding material which unites two adjacent blocks on the opposing grooved surfaces of the end walls thereof, said hollow 105 blocks being assembled in rows and superposed for the thickened web of each block to aline vertically with the opposing end walls respectively of two blocks above and below it and with the openings in said thickened web in vertical register with the bonding material uniting said end walls of the blocks, said walls and cross webs of each block being in vertical register with corresponding walls and cross webs of blocks in 110 the rows above and below the same.

5. A wall comprising hollow tile blocks each provided internally thereof with a thickened web and with a cross web positioned relatively to each other to produce 115 cells extending lengthwise of the block, said thickened web connecting the inner and outer walls of the block and said web being provided in the material composing it with openings separate from said cells, said 120 blocks being bonded together in rows to break joints and said blocks being superposed one upon the other for the walls and

webs of one block to aline vertically with the walls and webs of blocks above and below it, the cells of said superposed blocks being in vertical register, and reinforced 5 concrete material filling said registering cells of the superposed blocks and bonded to the walls thereof.

In testimony whereof I have signed my name to this specification in the presence of two subscribing witnesses.

PHILIP H. BEVIER.
